UNITED STATES PATENT OFFICE.

JOHN B. WILSON, OF LEADVILLE, COLORADO; AMIL M. ANDERSON ADMINISTRATOR OF
SAID JOHN B. WILSON, DECEASED.

MOTOR.

1,322,856.

Specification of Letters Patent. Patented Nov. 25, 1919.

Application filed January 18, 1917, Serial No. 143,150. Renewed July 2, 1918. Serial No. 243,052.

To all whom it may concern:

Be it known that I, JOHN B. WILSON, a citizen of the United States, residing at Leadville, in the county of Lake and State 5 of Colorado, have invented certain new and useful Improvements in Motors, of which the following is a specification.

This invention relates to motors and has special reference to turbines actuated by 10 water or steam. The invention seeks to provide a motor which may be rotated in either direction and by the use of which the loss of energy will be minimized. The invention seeks further to provide a turbine of novel 15 construction whereby the driving power of the fluid will be utilized to the fullest extent and the fluid will not be discharged until all of its energy has been exhausted.

The invention is illustrated in the accompanying drawings, in which:

Figure 1 is a view partly in plan and partly in section of a motor embodying my 20 improvements;

Fig. 2 is an enlarged detail section 25 through a portion of the rotor and the casing;

Fig. 3 is an enlarged vertical section taken 30 approximately on the line 3—3 of Fig. 1, the plane of the section being distorted so as to follow the rotor passages;

Fig. 4 is a view partly in elevation and partly in vertical section of the complete apparatus, the section being on the line 4—4 of Fig. 1;

Fig. 5 is a view, partly in section and partly in elevation, of the complete turbine 35 showing the parts separated but in their proper relative positions, the section being on a plane similar to that followed in Fig. 3;

Fig. 6 is a section taken through the inlet 40 for the motive fluid.

Fig. 7 is a similar view through the exhaust, the planes of the sections in Figs. 6 and 7 being similar to that followed in 45 Fig. 3.

In carrying out my invention, I provide a tank or boiler 1 which may contain a supply 50 of water or steam and which is connected with the casing 2 of the turbine through a pipe 3 having branches 4 leading to and into the turbine casing. These branches 4 will be equipped with valves 5 and will each communicate directly with an inlet chamber 6

within the casing 2, each inlet being arranged to discharge into the inlet ports of the buckets or pockets in a rotor. The casing consists of an annular wall 7 having inwardly projecting annular flanges 8 at its upper and lower edges and cap or cover plates 9 secured rigidly to the said flanges 55 by screws 10, as clearly shown. The said cap or cover plates are provided with extensions 11 having openings 12 therethrough to receive long screws or bolts by which the casing may be secured to any convenient 60 fixed support. A driving shaft 13 is fitted centrally through the cap or cover plates and journaled therein, packing boxes 14 being provided to prevent leakage around the shaft, as will be readily understood. As 65 shown in the drawings, two rotors are provided, both being keyed to the driving shaft 13 and being similar in construction but the supply nozzles 4 diverge from the pipe 3 so that they will deliver the fluid into the motor casing in such manner as to drive the 70 rotors in opposite directions. It will be readily understood that the flow through one or the other feeding nozzle is cut off, according 75 to the direction in which the driving shaft is to be rotated, and that at all times one rotor is a dead element. A central horizontal partition 15 is provided within the casing and is preferably formed integral 80 with the annular wall 7 of the same, as clearly shown. This partition 15 serves to separate the two rotors so that fluid admitted to one rotor cannot reach the other and, consequently, the driving shaft will be 85 driven in the desired direction. Upon the upper and lower sides of the partition 15, between the inner edge thereof and the outer wall 7, I provide the annular rib or projection 16, the outer face of which is inclined or beveled, as shown, so that the inner wall 17 90 of the rotor may rest thereon and form a ground joint therewith to avoid leakage of the fluid while at the same time being capable of rotating freely. In the inner face of each cap plate 9 is formed an annular groove 18 95 which receives the upper edge 19 of the inner wall of the rotor and the inner wall of the said groove is suitably shaped to receive a rib 20 on the inner or rear face of said wall 100 of the rotor. The inner wall 17 of the rotor 105 is connected with the hub 21 by spokes or

radial arms 22 and the hub is fitted around and keyed to the driving shaft, as will be readily understood, so that motion of the rotor will be imparted directly to the shaft. 5 From the wall 17 of the rotor a plurality of partitions 23 extend at an angle to the radius of the rotor and pockets or buckets 24 are formed between the partitions. The pockets are of the same form in the two rotors 10 but are reversed so that the fluid admitted to one turbine will tend to propel the same in a direction opposite to the direction in which the other rotor is driven. Each pocket has an inlet opening 25 in the outer surface 15 of the rotor and adjacent the outer end of the same, that is to say, the inlet ports of the buckets in the upper rotor are located immediately adjacent the upper cap or cover plate 9 while the inlet ports of the lower rotor are 20 located immediately adjacent the lower cap or cover plate. The bucket consists of a passage leading from the inlet port and deflected so as to utilize the space furnished by the groove 18 in the cap plate as a part of 25 the passage. The passage-way then extends downwardly along the outer face of the inner wall 17 of the rotor and terminates in the outlet 26 which is located immediately adjacent the partition 15 and utilizes the 30 said partition as one of its walls. Between the adjacent partitions 23, I provide a directing plate 27 which defines the inner wall of the passage-way or bucket and may be a sheet metal plate stamped into the proper 35 form or may be cast with the rotor. This plate or wall 27 may be filled with a block of wood or other light material so that fluid cannot collect between the sides or ends of the said plate, but will be forced to flow 40 through the passage-way or bucket and thereby impart motion to the rotor. The outlet port 26 is located somewhat in advance of the inlet port 25, considered in the direction of rotation of the turbine, so that 45 in flowing through the bucket or passage-way the fluid will not tend to retard the rotor, but will serve, by its tendency to expand, to maintain the motion imparted to the rotor by the initial impact of the fluid 50 against the forward wall of the pocket.

The fluid will travel around the casing with the rotor and just before it again reaches the vertical plane of the inlet, will pass into the exhaust chamber communicating with the exhaust pipe 29. At each side of and immediately adjacent the inlet nozzle 6, the inner wall of the casing is unbroken, as shown at 30, so that said wall forms an abutment to prevent escape of the 55 fluid except into and through the inlet port of the pocket which may be in alignment with the inlet nozzle. Beginning at one terminal of the abutment surface 30 and continuing around the casing to the other terminal of the abutment surface, the casing is 60

constructed with a series of expansion pockets 31 which open toward the rotor and have their inner terminals disposed immediately adjacent the edge of the rotor so that the joint will be sufficiently close to prevent 70 leakage while at the same time it will be sufficiently free to permit rapid and easy rotation of the rotor. These pockets 31 are constructed with upper and lower ports disposed in the same transverse planes of the 75 rotor as the inlet and outlet ports of the rotor pockets so as to register therewith, as shown clearly in Fig. 3, and division blocks 32 are formed in the wall of the casing between the ends of the said pockets so that 80 the fluid will be forced to travel around the blocks and cannot flow directly through the inlet port to the exit port. The pockets in the casing are disposed at a somewhat greater angle to a vertical plane than are 85 the pockets in the rotor so that as the rotor moves past the pockets in the casing, the fluid in the rotor pocket will flow from the inner or lower or exhaust port of the said pocket into the lower or inner inlet port of 90 the pocket in the casing and will expand in said pocket so that it will rise therethrough and escaping through the upper outlet port of the same will meet and flow through the inlet port of a pocket in the rotor, thereby 95 accelerating the movement thereof. This action of the fluid will be accelerated as the turbine attains greater speed for the reason that a suction will be created around the 100 rotor which will tend to draw fluid through the casing pockets and cause it to again enter the rotor pockets with considerable force.

In the foregoing description, I have been referring to the upper rotor for the sake of 105 convenience, but it is to be understood that the terms upper and lower, inner and outer are relative only and that the operation of the lower turbine is exactly the same except that it rotates in the opposite direction and 110 that the inlet port of a pocket in the lower turbine will be the lower port while the outlet port of said pocket will be the inner or upper end thereof. It is also to be understood that while I have assumed the driving 115 shaft to be disposed vertically, it may be disposed horizontally and that various other modifications in the specific arrangement may be made without involving any departure from the present invention.

The exhaust from the two turbines may be led into a single pipe 29 and through said pipe into an exhaust receiver 33 which consists of a casing 34 of any convenient form having an outlet 35 which may lead 125 to any convenient point of discharge or may be connected to the tank or boiler 1 so that the fluid may be returned to the point of supply and thence again sent through the turbine to be utilized. Within the recep- 130

tacle 33 is a partition 36 disposed between the exhaust pipe 29 and the outlet 35 and having a top member 37 by which the interior of the receptacle is divided into an upper and a lower chamber. Through the top member or plate 37 is formed an opening from the edge of which depends a collar 38 and in the upper portion of the receptacle is provided an opening 39 within a boss 40 to which a pump may be connected for creating a suction through the receiver. The pump (not shown) may be driven from the turbine and will tend to create a vacuum within the receiver 33 so that the exhaust fluid will be effectually withdrawn from the turbine and will, therefore, offer no resistance to the proper operation of the same. By forcing a circulation through the receiver from opening 39 to outlet 35 I create a partial vacuum in or suction through the receiver so as to effectually withdraw the exhaust fluid, the top plate 37 of the partition serving to hold back the fluid which by a direct flow would tend to interfere with the creation of a partial vacuum. I also create a partial vacuum within the turbine and this partial vacuum will facilitate the operation of the fluid within the pockets of the casing to repeatedly act on the rotor, as above set forth.

From the foregoing description, taken in connection with the accompanying drawings, it will be seen that I have provided a rotor which may be readily set up and which, when operated, will be found highly efficient and economical. It will be readily understood that the wall or division block 32 in the rotor casing effectually separates the opposite ends of the buckets or pockets and that the inlet nozzles are so disposed that they will communicate only with the inlet ports of the rotor casing and the exhaust nozzles or pipes are so disposed that they will communicate only with the outlet ports of the pockets. The motive fluid, therefore, cannot pass simultaneously to both ends of the pockets but will be forced to flow entirely through the pockets from one end of the same to the other end and the initial impulse will be sufficient to carry the pocket of the rotor to the point where its outlet end will communicate with the inlet end of the first pocket in the casing. As the pocket in the casing is at a greater inclination than the pocket in the rotor, the rotor pocket will be drained by the time its inlet end comes into alignment with the outlet end of the pocket in the casing and the fluid in the casing pocket will then again enter the rotor pocket and by its expansion will aid in driving the rotor. By providing the annular grooves in the cap plates, as shown and described, and projecting parts of the rotor into said grooves, I not only produce pockets of considerable capacity in the rotor but

also mount the rotor in such a manner that it will be effectually guided in its movements and will not oscillate at an angle to the axis of the driving shaft and, as lost motion generally due to such oscillation is 70 eliminated, the rotor will move easily and smoothly and the loss of energy from the propelling agent will be minimized.

Having thus described the invention, what is claimed as new is:

1. In a motor, the combination of a casing provided in one end wall with an internal annular groove and provided on its opposite end wall with an annular rib, a shaft journaled in the casing, a rotor secured to said shaft and provided with an inner peripheral wall having portions engaging said annular groove and said annular rib, and pocket-forming passages in the rotor at the outer side of said wall, one of said passages extending across the inner peripheral wall of the rotor and the other passage extending from the ends of said passage between the rotor and the end walls of the casing.

2. In a motor, the combination of a casing, a rotor mounted therein and having an inner peripheral wall fitting closely to and guided by the end walls of the casing, partitions extending outwardly from the said peripheral wall, and fillers disposed between 95 said partitions and connected therewith and bearing at their outer ends against the casing and having their sides in spaced relation to the end walls of the casing and the inner peripheral wall of the rotor whereby 100 tortuous fluid-receiving passages are provided around the fillers.

3. In a motor, the combination of a casing consisting of an annular wall, caps secured upon the ends of said wall, and a partition extending from the inner surface of said wall between the caps, the caps being provided on their inner faces with annular grooves and the partition being provided with ribs on its opposite sides, a rotor having an inner peripheral wall having its edges obliquely disposed to bear against the inner walls of the grooves in said caps and upon the outer faces of the ribs on the partition respectively, partitions extending from 105 the peripheral wall, and fillers disposed between the partitions and in spaced relation to said peripheral wall of the rotor, the partition in the casing, and the caps whereby a fluid passage is provided around the filler 110 and between the partitions.

4. In a motor, the combination of a casing having an annular wall, and a central partition carried by said wall, obliquely disposed passages being provided in the annular wall of the casing, caps secured upon the ends of the annular wall of the casing and provided in their inner faces with annular grooves, a rotor mounted between the partition and a cap and having an inner periph- 125 130

eral wall with its edges fitting snugly within the groove in the cap and against a rib on the partition, partitions extending from the said inner peripheral wall of the rotor, and 5 fillers disposed between the partitions in spaced relation to the cap, the partition of the casing, and the inner peripheral wall of

the rotor whereby passages are provided around the fillers having their ends adapted to register with the ends of the passages in 10 the casing.

In testimony whereof I affix my signature.

JOHN B. WILSON. [L. s.]
